METHOD OF MAKING CUSHION SUPPORTING
MEMBERS

Norman Grimshaw, Ashton-under-Lyne, England, assignor to Vitafoam Limited, a company of Great Britain
Original application Sept. 25, 1961, Ser. No. 140,436, now Patent No. 3,125,156, dated Mar. 17, 1964. Divided and this application July 29, 1963, Ser. No. 298,352
1 Claim. (Cl. 156—245)

This is a divisional application of the U.S. application Serial No. 140,436 filed September 25, 1961, which is issued as Patent No. 3,125,156 on March 17, 1964.

This invention concerns supports, to be attached to the framework of a piece of furniture, for supporting for instance, a cushion. The term furniture is to be construed as including motor vehicle seating, household seating, bedding and the like, and also rail and aircraft seating, sea transport seating, bedding, and the like.

Throughout the following description only chair seating will be referred to for simplicity.

It is well known to use as the cushion support for a chair, interwoven bands of webbing, which may be resilient or otherwise, springs, combinations of springs and wires and also non-interwoven bands normally of rubber or rubberized fabric.

One of the difficulties associated with the methods used for securing cushion supports lies in the length of time taken to secure the support to the frame.

Moreover in some cases the support given to the cushion has been unevenly distributed and localized and relatively large non-supported areas exist which tend, after a period of use, to result in deformation of the cushion.

The object of the present invention is to provide a method for forming an improved support which can easily be attached to the furniture frame and will tend to give an even support to the cushion.

Another object of the present invention is to provide a method of making a support for furniture by moulding a sheet of thermoplastic material into a U-shaped metal fastening member by placing the material in a mould together with the fastening member, subjecting them to pressure and heat and causing the material to flow in between the U-shaped member. A more specific aspect of the invention further provides the member with holes and the material is caused to flow into said holes, thereby being keyed therein.

Another object of the present invention is to provide an improved method of making a support for a cushion or the like. A more specific aspect of this object is to provide a method for simultaneously curing a sheet of thermoplastic material and bonding a plurality of metal attaching members thereto in a particularly efficient manner.

The invention will be described further, by way of example, with reference to the accompanying drawings which illustrate diagrammatically a form of support and the manner in which such is attached to the framework of an article of upholstered furniture, and in which:

FIG. 1 is a diagrammatic plan view of one form of the support;

FIG. 2 is a perspective view of a tongue of the support shown in FIG. 1, but on an enlarged scale;

FIG. 3 is a perspective view of a corner of the support of FIG. 1 when attached in one possible manner to the framework of an article of furniture to be upholstered;

FIG. 4 is a part sectional view showing a modified means of attachment to the framework;

FIG. 5 is a view similar to that of FIG. 3 showing the modified means of attachment;

FIG. 6 is a part sectional elevation showing a means for attaching the support to the framework; and

2

FIG. 7, 8 and 9 are detail sections on an enlarged scale showing various means for the attachment of the support to the framework.

Like reference numerals on the several figures of the drawings denote like parts throughout the specification.

FIG. 1 illustrates a cushion support comprising a sheet of rubber which is moulded to provide a support area 10 having outwardly extending tongues 11. Considering the extremities of the tongues 11 as defining the overall size of the support, it is approximately rectangular in shape with cut-outs 12 along each side. The cut-outs 12 are two in number on each side of the support 10 and thus tongues 11 are formed at the four corners and in the central region of each side.

Within the area 10 are a plurality of apertures 13 which may be of any suitable shape and disposition depending upon the use to which the support is to be put.

The tongues 11 are each provided with a metallic member bent into the form of a U having one arm longer than the other. The longer arm 14 is provided with a locating flange 15 at its end and the flange is directed away from the shorter arm 16. Aligned holes 17 are made in the arms for a purpose hereafter referred to.

To secure the member so formed to the tongues 11 the members are treated with a bonding agent and the uncured material for the support, together with the members are suitably placed in a metal mould and the assembly so formed is subjected to pressure and heat to cure the rubber and bond the members thereto. Whilst the assembly is in the mould, rubber flows into the holes or recesses 17 in the members and ensures efficient bonding by keying the rubber to the members.

In the modified form of attachment shown in FIGURE 4, the member comprises a metal strip 20 of substantially question mark shape. In the straight portion 21 of the member are drilled a number of holes 22, for example three, the purpose of which is to provide for efficient bonding of a rubber strip to the member.

The member is treated on its outer surface (the surface of larger radius insofar as the arcuate portion is concerned) with a chemical bonding agent and is placed in the mould with the uncured rubber for the support and a bond is formed in the manner described above.

The support so formed is clipped on to a tubular member 23 which is part of the framework of a chair in the manner shown in FIGURE 5.

FIGURES 7, 8, and 9 illustrate various forms of a device which may be attached to the members described to enable the support to be attached, under tension to an article of furniture. The attachment device is located by means of locating flange 15. FIGURE 6 shows a support attached to part of the framework of an article of furniture by the device illustrated in FIGURE 7.

FIGURES 7 and 9 illustrate an attachment device of L-shape. One arm of the L is provided with apertures which correspond in size and disposition to the holes 17 of the members above described. The device is secured to the support by means of rivets 18, studs or the like and proper assembly is facilitated because of the alignment of the holes due to the locating flange 15. The other arm of the L is provided either with holes through which can pass screws, nails, pins or the like 19, as shown in FIGURE 7 or with punched out spikes 20 as shown in FIGURE 9.

In the modification illustrated in FIGURE 8, the device is of question mark form and is especially adapted for use with tubular steel furniture.

The unstretched area of the support 10 is less than the area for it as defined by the chair frame.

In use, the support 10 is secured to the framework

by stretching it and securing the members to the framework by one of the methods above referred to.

The invention is not restricted to the above details. For example, the support can be moulded to any shape or size and the corner tongues may be omitted.

Various modes of carrying out the invention are contemplated as being within the scope of the following claim particularly pointing out and distinctly claiming the subject matter which is regarded as the invention:

The method of making a support for furniture by simultaneously moulding and curing a sheet of rubber and also bonding it to a plurality of flat U-shaped metal fastening members each having a pair of parallel arms with recesses therein, comprising the following steps; placing uncured rubber and the U-shaped members in a

5 mould, subjecting said rubber and U-shaped members to sufficient pressure and heat to cure said rubber and make it resilient and also bond it into said recesses and in between said arms, positioning an apertured attachment device against said fastening member and said flange to thereby align the apertures in said device with the recesses in said member, and securing said fastening device to said U-shaped, fastening member by inserting at least a part thereof through said apertures and said recesses to thereby remove at least a portion of said cured rubber therefrom.
